US0D1053345S

(12) **United States Design Patent** (10) Patent No.: **US D1,053,345 S**
Shen et al. (45) Date of Patent: ** Dec. 3, 2024

(54) **RESPIRATORY MUSCLE TRAINER**

(71) Applicant: **JIAXING KAIQI HEALTH TECHNOLOGY CO., LTD.**, Jiaxing (CN)

(72) Inventors: **Shanmei Shen**, Jiaxing (CN); **Weidong Su**, Jiaxing (CN); **Yan Ma**, Jiaxing (CN); **Shengui Li**, Jiaxing (CN); **Leifeng Zhu**, Jiaxing (CN); **Binxin Ma**, Jiaxing (CN)

(73) Assignee: **JIAXING KAIQI HEALTH TECHNOLOGY CO., LTD.**, Jiaxing (CN)

(**) Term: **15 Years**

(21) Appl. No.: **29/823,585**

(22) Filed: **Jan. 18, 2022**

(30) **Foreign Application Priority Data**

(57) **CLAIM**

The ornamental design for a respiratory muscle trainer as shown and described.

DESCRIPTION

FIG. 1 is a first perspective view of the respiratory muscle trainer showing the design;

FIG. 2 is a second perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines in the drawings depict portion of the respiratory muscle trainer and form no part of the design.

1 Claim, 7 Drawing Sheets
